UNITED STATES PATENT OFFICE.

JAMES S. ANDREWS, OF NEW YORK, N. Y.

UNDERFRAME FOR CARS

No. 865,669.

Specification of Letters Patent. Patented Sept. 16, 1907.

Application filed June 7, 1907. Serial No. 377,721.

To all whom it may concern:

Be it known that I, JAMES S. ANDREWS, a citizen of the United States, residing at New York, in the county of New York and State of New York, have invented 5 new and useful Improvements in Underframes for Cars, of which the following is a specification.

This invention relates to underframes for railway cars and its object is primarily to provide a metal under-frame of strong and substantial construction and composed of standard sections consisting of steel castings 10 securely and rigidly fastened together.

Another object of the invention is to reduce the cost of manufacture, assembling and repairing underframes for railway cars by making the sections according to a 15 comparatively few patterns, and so as to be interchangeable, and assembling them in a manner which will permit the sections to be easily replaced.

In the accompanying drawings I have illustrated one embodiment of the invention and referring thereto

20 Figure 1 is a top plan view of the underframe. Fig. 2 is a bottom plan view. Fig. 3 is an enlarged longitudinal sectional view on the line 3—3 of Fig. 1. Fig. 4 is an enlarged transverse sectional view on the line 4—4 of Fig. 1. Fig. 5 is a detail enlarged perspective view 25 on the line 5—5 of Fig. 1. Fig. 6 is a similar view on the line 6—6 of Fig. 1.

Referring to the drawings the side sills consist of two end sections 7 and a central section 8, these end sections being made of cast steel in channel form (Fig. 4, 5). 30 The central section 8 is also preferably made of cast steel in channel form to abut against the ends of the end sections 7. The sections 7 and 8 of the side sills are securely and rigidly fastened together by tie plates 9, 9' which overlap the adjacent ends of these sections and 35 are riveted or bolted thereto. The tie plate 9 (Fig. 5) is made in channel form to fit in the channel side of the side sill and the tie plate 9' is made flat and placed on the outside of the side sill sections. At each end of the frame is a draw-bar sill 10 which is provided with an 40 opening 11 to receive the draw-bar and its attachments. The draw-bar sill is made of cast steel and is provided with side projections 12 to abut against integral side projections 13 on the sections 7 of the side sills to form the body bolster. The draw-bar sill is also provided with 45 integral side projections 14 to abut against integral side projections 15 on the sections 7 of the side sills to form the end sill. The draw-bar sills are also provided with integral side projections 16 which constitute parts of the center sill and abut against the cast steel intermediate 50 section 17 of the center sill. The projections 16 and the intermediate sections 17 of the center sill are made in I-form and are securely and rigidly fastened together at their adjacent ends by over-lapping channel tie plates 18, 18' which are riveted or bolted to said sections (Fig. 6). The projections 12 and 13 are also made in I-form and are securely fastened together by channel

plates in the same manner shown in Fig. 6. The projections 14 and 15 are made in channel form and are securely fastened together in the manner shown in Fig. 5. The projections 12 are provided with integral side bearings 12' (Fig. 4). The transoms 19 are preferably made of channel iron and riveted or bolted at their ends to integral lugs 20 on the side sills (Fig. 1) and similar lugs 20' on the center and draw-bar sills (Fig. 3).

The underframe is made almost entirely of steel castings and is strong and substantial in construction. Many of the parts are duplicates and can be made with the same patterns which not only reduces the cost of manufacture but also the cost of repairing and replacement. The sections of the underframe are made so that they can be easily secured together in a strong and rigid manner and so that any section can be readily removed and repaired and replaced without taking the entire frame apart.

What I claim and desire to secure by Letters Patent 75 is:

1. An underframe for cars comprising a metal side sill provided with an integral projection extending part-way between the side sill and the draw-bar sill to constitute a part of the end sill. 80
2. An underframe for cars comprising a metal side sill, said side sill comprising a cast steel end section provided with an integral projection extending part-way between the side sill and the draw-bar sill to constitute a part of the end sill. 85
3. An underframe for cars comprising a metal side sill composed of a plurality of sections, the two end sections of said side sill being made of cast steel and each provided with an integral projection constituting a part of the end sill. 90
4. An underframe for cars comprising a metal side sill, said side sill comprising a cast steel end section provided with an integral projection constituting a part of the end sill, and an integral projection constituting a part of the body bolster. 95
5. An underframe for cars comprising a metal draw-bar sill provided with integral side projections constituting parts of the end sill. 100
6. An underframe for cars comprising a metal draw-bar sill provided with integral side projections constituting parts of the end sill and integral side projections constituting parts of the body bolster. 105
7. An underframe for cars comprising two metal side sills, each of said side sills having an end section provided with integral projections constituting parts of the end sill and integral projections constituting parts of the body bolster, and a metal draw-bar sill provided with integral projections constituting parts of the end sill and integral projections constituting parts of the body bolster. 110
8. An underframe for cars comprising a metal side sill consisting of two cast steel end sections and a cast steel intermediate section, all of said sections being made in channel form, a channel tie plate overlapping the adjacent ends of said sections on the channel side thereof, a flat tie plate overlapping the adjacent ends of said sections on the flat side thereof, and means for securing said tie plates to the sections. 115
9. An underframe for cars comprising two cast steel draw-bar sills provided with end projections in I-form to constitute parts of the center sill, an intermediate section 120

in I-form to abut against the ends of said projections, channel tie plates overlapping the adjacent ends of said sections, on both sides thereof, and means for securing said tie plates to the sections.

- 5 10. An underframe for cars comprising a metal side sill, said side sill comprising a cast steel end section having an integral side projection to form part of the end sill, a cast steel draw-bar sill having an integral side projection to abut against the side projection on the side sill section 10 and form part of the end sill, said projections being made in channel form, a channel tie plate overlapping the ends of said projections on the channel side thereof, a flat tie plate overlapping the ends of said projections on the flat side thereof, and means for securing said tie plates to the 25 projections.

11. An underframe for cars comprising a metal side sill, said side sill comprising a cast steel end section, provided with a side projection to constitute a part of the body bolster, a cast steel draw-bar sill provided with an integral side projection to abut against the projection on the side sill section and constitute a part of the body bolster, said projections being made in I-form, channel tie plates overlapping the ends of said projections, and arranged on both sides of the projections, and means for securing the tie plates to the projections. 20

JAMES S. ANDREWS.
